Twister Corporation, Jersey City, N. J., a corpora-
tion of New Jersey

Application March 27, 1951, Serial No. 217,739

8 Claims. (Cl. 57—58)

1

This invention relates to a device for imposing tension upon elongated flexible material travelling under tension in the direction of its length. More particularly, the device of the invention provides means for automatically adding to the initial tension of the material a sufficient added variable tension to render the tension on the material leaving the device substantially constant and of a desired predetermined amount.

In a preferred embodiment thereof, the invention relates to a device for controlling the tension at the infeeding end of a balloon of a take-up twisting spindle, and to the combination of such device with one or more supply spindles each delivering twisted material therefrom in the form of a balloon, the material being fed directly from such supply balloon or balloons into the infeeding balloon of the second, take-up, twisting spindle, or twisting and cabling device. In such combination the compensating device of the invention functions to maintain a balance between the tension or tensions in the supply balloon or balloons and the tension in the balloon of the second, take-up, twisting spindle, or the cabling and twisting device.

In the illustrative embodiment of the tension compensating device here disclosed, it is shown in the same general combination of twisting apparatus for elongated flexible materials such as yarn as that shown in Uhlig Patent No. 2,487,837, November 15, 1949, and also that shown in the application of Bogdanffy et al., Serial No. 59,392, filed November 10, 1948, and the application of Henry C. Uhlig, Serial No. 127,380, filed November 15, 1949, both such applications being entitled "Apparatus for and Method of Cabling Threads." The apparatus of the present invention is designed, in the illustrative embodiment, to replace the driven gathering pulley 33 and the tension compensating device 35 of the aforesaid Uhlig patent, and to replace the frictionally braked gathering pulley 66, 68 of the aforesaid Bogdanffy et al. and Uhlig applications. The device of the present invention provides a means for much closer control of the cabling and twisting balloon of the take-up spindle than is possible with the above referred to prior apparatus. The device of the invention imposes a first, substantially constant, tension upon the gathered, as yet untwisted-upon-each-other, strands of material issuing from the balloons of the supply spindles, whereby to effect a balance between such tensions and the tension in the balloon of the take-up or cabling and twisting spindle when the latter is at its optimum diameter. The de-

2

vice further incorporates means for detecting the tension in the balloon of the take-up spindle, and for automatically adding tension to or subtracting it from the aforesaid substantially constant tension, so that when the tension in the take-up balloon deviates from an optimum value it is quickly restored thereto, and that consequently the diameter of such take-up balloon is maintained of a substantially constant diameter.

10 The invention is capable of use to advantage in other applications than that shown and described. Such device may be used, for example, in many other applications involving the feeding of elongated flexible material from a first zone, in which it is under an initial smaller tension, into a second zone of larger tension, such larger tension tending to vary, where it is desired to maintain the second larger tension substantially constant.

15 20 The invention will be more readily understood by reference to the accompanying drawings forming a part of the specification, in which:

Fig. 1 is a somewhat schematic view in front elevation of a three-spindle twisting apparatus employing the compensating device of the invention;

Fig. 2 is an enlarged view in front elevation of the tension compensating device;

Fig. 3 is a view in end elevation of the compensating device, such view being taken from the line 3—3 in Fig. 2;

Fig. 4 is a view in perspective of the compensating device, showing the path of travel of the elongated flexible material therethrough;

Fig. 5 is a fragmentary view in end elevation showing the relationship between the friction disc of the device, for causing the imposition of a variable tension upon the material, and the material upon which it acts, in the position which such disc assumes when the tension in the balloon of the spindle to which the material is fed is at the desired optimum amount;

Fig. 6 is a view similar to Fig. 5 showing the relationship between the material and the friction disc which is momentarily assumed when the tension in the aforesaid balloon has exceeded the optimum value; and

Fig. 7 is a view similar to Figs. 5 and 6 showing the relationship between the friction disc and the material operated upon when the tension in the balloon to which the material is fed has momentarily decreased below said optimum value.

In Fig. 1 there is shown the same general combination of twisting apparatus as is shown in

Fig. 1 of each of the above mentioned Bogdanffy et al. and Uhlig applications, the compensating device of the present invention being substituted in such combination for the gathering pulley 60 and the friction braking means 66, 68 associated therewith shown in said applications. In Fig. 1 of the present application there are shown two singles spindles 2 and 4 which two-for-one twist elongated flexible material such as flat rayon yarn supplied from bobbin or package 34, such spindles delivering the double-twisted material therefrom in balloons 46 and 54, respectively. As shown in connection with spindle 2, such elongated material 44 is delivered from the package through the tension device 38, down through the driven twisting guide 40 in the spindle 41, and is then delivered outwardly into the balloon 46 through the flyer 42. The double-twisted materials 50 and 58 are delivered, as shown, upwardly through their respective eyes 48 and 56 to the compensating device 60 of the invention, to be described more particularly hereinafter. From such compensating device the material, designated 80, and consisting of the two strands 50 and 58 in generally parallel relationship, but as yet untwisted upon each other, is led downwardly through the eye 82 into the balloon 84 of the cabling and twisting take-up spindle 6. The material from balloon 84 enters at its lower end into the flyer 92, and then rises upwardly along the axis of the spindle 6. Such material is substantially positively pulled from the balloon 84, to be forwarded to the cord laying pulley 144 on traverse device 146, by means of the capstan 196, which is positively driven in timed relationship with the flyer 92 of spindle 6. The cord is laid upon the bobbin 126 of the spindle by the guide pulley 144, the bobbin being driven from the driven spindle through the medium of a variable magnetic clutch 103. The details of the apparatus thus far described, which are fully disclosed in the above mentioned patent and applications, form no part of the present invention except as they contribute to the general combination of the twisting apparatus and the present compensating device. The twisting spindles 2, 4, and 6 are driven through pulleys 22, 24, and 26, respectively, which contact the belt 32 driven by pulley 20 on motor 16. As shown, for the particular application in hand, the two spindles 2 and 4 are driven in one direction, and spindle 6 is driven in the reverse direction.

The compensating device of the invention, which is designated generally by the reference character 60, is attached, as shown in Figs. 1 and 2, to the horizontal frame member 62 of the twisting machine. On the machine, in such location that the material 80 is delivered to the eye 82 along a substantially vertical path as the apparatus is depicted in Fig. 1, there is located the standard 64 which is provided with an enlarged head 66. Head 66 is slotted to provide vertically extending ears 68, there being a generally horizontal first-class lever 70 pivotally carried between the ears on pivot pin 72. On top of the ears 68, which are of such height as to allow free oscillation of lever 70 between desired limits, there is secured the base 74 of an upper standard part 76. Standard 76 has a head 78 which supports the upper elongated member 86 in horizontal position, the rear, reduced diameter, portion 88 of member 86 being received in a bore in head 78 and being pinned thereto.

The forward end 90 of member 86 carries on its outer end the double-grooved guide pulley 96, 75

such pulley being freely rotatably mounted upon the pin 94 which secures it to member 86. The rear groove in pulley 96, which constitutes a first fixed position guide, is designated 100 and the front groove, which constitutes a second fixed position guide, is designated 98. The forward arm 102 of lever 70 carries on its outer end, by means of the pin 106, the freely rotatable composite member 108 which combines the guide pulley having the groove 110 and the brake member actuating disc 112.

Under operating conditions, as will be more fully explained, the lever 70 is constantly urged in a counterclockwise direction, as it is shown in Fig. 3, by means of the coil tension spring 136 which has its top end fixedly secured to the rear end of the upper supporting member 88. The bottom end of the spring 136 is adjustably connected to the rear arm 104 of lever 70 by means of the L-shaped connector member 150, to the upper end of the vertical portion of which the spring 136 is connected. The lower portion 154 of connector 150 carries screwed thereto the vertical set screw 152, the upper end of such screw fitting within one of a series of longitudinally disposed complementary depressions 156 on the bottom surface of arm 104. By such structure the spring 136 may be subjected to a desired initial tension by positioning the upper end of screw 152 in the desired depression 156 with such screw in, for example, its midposition relative to part 154. Further, finer, adjustment of the tension of the spring may be secured by screwing member 152 into, or withdrawing it from, the member 154. As a result, the force with which lever 70 is impelled in a counterclockwise direction may be so selected as to maintain a predetermined optimum tension in material 80 issuing from the compensating device.

The friction disc 112 is made up of the two spaced parallel flanges having the groove 122 therebetween, the forward flange being designated 113 and the rear flange 120. The groove 122 extends from the periphery of the disc inwardly to the root 124 thereof. The relationship between the grooves 98 and 100 of the upper guide pulley 96, the grooves 110 and 122 of the bottom structure 108, and of eye 82 is shown in Figs. 1, 3, 5, 6, and 7. When the lever 70 is in its normal position corresponding to the optimum tension in the take-up balloon, that is, when the axis A—A of such lever lies parallel to member 86, as indicated in Fig. 5, grooves 100 and 110 are vertically aligned. When the lever is in such position, the material 134 proceeding from the groove 98 into the groove 122 of the friction disc and thence, as material 80 into eye 82, contacts the inner face 158 of the flange 120 of member 108 from its initial contact at the upper inner corner 162 to a point somewhat above the axis of disc 108, at which point it leaves such surface 158, as shown in Fig. 5. The root 124 of groove 122 in structure 108 has a diameter substantially the same as the smallest diameter of groove 98, and the axes of members 96 and 108 are in vertical alignment, whereby the material 134 will contact such root 124 of structure 108 lightly, if at all, in its travel downwardly through the slot in the friction disc.

The twisted single strand 58 is brought up from eye 56 once around pulley 114 of the yardage counter 116, from which it proceeds to the top of groove 100 in guiding pulley 96. The twisted strand 50 is brought up to the under side of

groove 100. The two strands are thus combined at such groove and after passing over the top of the groove are led directly therefrom down into the groove 110 on structure 108. Such run of the material is designated 130, being most clearly shown in Fig. 4. The two strands are wrapped about the groove 110, preferably for substantially two complete turns, so that substantially no slippage takes place between the material and the groove 110 of the pulley. The two parallel strands are then led upwardly from groove 110 in a run designated 132 to the groove 98 of pulley 96, the runs 130 and 132 of the strands impelling pulley 96 in the same direction. After passing over the top of groove 98, the two parallel strands are then led, in the run 134, directly down through the slot 122 between the flanges 112 and 120, the material below such friction disc being designated 80. The material 80, as shown in Fig. 1, then enters the eye 82 after which it is formed into the take-up balloon 84.

As above indicated, the compensating device 60 of the invention functions to maintain the tension in balloon 84, and thus the diameter of the balloon, substantially constant. When the heavier, multi-filament materials such as yarns of 1650 and 2200 denier, for example, are twisted in the apparatus, the tension in balloon 84 substantially exceeds the sum of the tensions in balloons 46 and 54. Accordingly, to maintain the take-up balloon in substantial balance with the singles balloons it is necessary to add a retarding tension to the material between the singles balloons and the take-up balloon.

Device 60 imposes a first, substantially constant, retarding tension to the material passing therethrough by reason of the internal friction in the material itself as it is bent around the pulley grooves 100, 110, and 98, and also by reason of the friction between such material and the surfaces of the pulley grooves. Such first added tension does not change materially, even though the lever 70 pivots slightly about its horizontal axis in a manner to be explained. In addition to the above referred to substantially constant tension imposed on the material by device 60 there is also the substantially constant retarding tension imposed on the material by reason of the passage of strand 58 once around the counter pulley 114.

Device 60 imparts a second, automatically varied, tension to the material passing around pulley groove 110 thereof, as a result of the interaction between such elongated flexible material and the flanges 118 and 120 of friction disc 112. It will be apparent that disc 112 is substantially positively rotated by means of travel of the cord around groove 110. When the lever 70 lies substantially parallel to member 90, with the tension in balloon 84 at its optimum value, frictional contact between the run 134 of the material and the disc 112 is, as shown in Fig. 5, confined to a distance somewhat less than one-half the height of the disc at a point beginning at the upper inner corner 162 of face 158 of flange 120. The major variable frictional restraint thus imposed upon the material by groove 110 of means 108, such means 108 being retarded by the interaction between the material in run 134 and disc 112, and also the smaller variable frictional restraint imposed on the material by contact with disc 112 itself, taken in addition to the restraint at pulley 114 and also the restraint by reason of the passage of the material about grooves 110, 100, and 98, is sufficient to create a

balance between the tension in balloon 84 and the sum of the tensions in balloons 46 and 54.

In the machine described the sum of the tensions in balloons 46 and 54 does not appear to vary substantially. The main variant in the system, which has caused difficulties in the control of balloon 84, has been the variation in tension in such balloon 84. The device 60 of the invention, by providing means for automatically varying the retarding effect upon the material by groove 110 as governed by friction disc 112, automatically compensates for such variations in tension in balloon 84. In Fig. 6 there is shown somewhat schematically the relationship between disc 112 and the run 134 of the material passing therethrough upon an increase in tension in balloon 84. When such increase in tension occurs, it is immediately reflected in an increased tension in run 132 of the material in device 60. Such increased tension in run 132 causes the lever 70 to rotate clockwise against the action of spring 136 (Fig. 3), thereupon supplying an increased length of material to the balloon 84 to prevent its being pulled inwardly into contact with the rub ring 140 on the spindle 6. Such slight rotation of the lever 70 causes the disc 112 to assume the angular relationship shown in Fig. 6, wherein the axis A—A of the disc lies, at the right, at an angle B below the normal position thereof. When the disc 112 has attained such position, the material 134 is freed from contact with side walls 158 of flange 120, and the disc will not have swung sufficiently to cause contact between such material and the side wall 160 of flange 118. Consequently, the frictional retardation imposed on disc 112 by the material falls substantially to zero, and means 108, including groove 110, rotates freely. The tension upon the material entering balloon 84 is accordingly decreased, and thus, due to the corresponding decrease in tension in run 134 of the material, the lever 70 is allowed, under the action of spring 136, to resume the normal operating position shown in Fig. 5.

When the tension in balloon 84 has decreased from the normal optimum tension, the disc 112 assumes the position shown in Fig. 7, wherein the lever 70 has turned counterclockwise (Fig. 3) sufficiently to allow the axis A—A of disc 112, at the right, to lie an angle C above the normal position thereof. When the disc occupies such position, the material in run 134 is, in effect, pinched between the side walls 158 and 160 of flanges 120 and 118, respectively, the contact being most forceful at the outer edges 162 and 164 of such flanges, respectively. The disc 112 thus imposes a markedly increased retardation upon the rotation of means 108, including groove 110, over that which it imposes in its normal operating position shown in Fig. 5, so that the material enters balloon 84 under increased tension, and the balloon is prevented from "blowing out." When the desired tension has been restored to balloon 84, the tension in run 132 accordingly rises and the lever 70 is restored to the position represented in Fig. 5.

Since the disc 112 need contact run 134 of the material only lightly, due to the large diameter of such disc relative to groove 110 of the retarding guide roll, the tension in balloon 84 is transmitted substantially unchanged to run 132 of the material. When the sum of the tensions in the singles balloons remains at least generally constant, as it appears to do in the combination disclosed, the main variant in the forces opposing the action of spring 136 on groove 110 of the

roller guide is the tension in the double balloon 84. The roller guide with its mounting therefore constitute a means for detecting or measuring tension, and the changes in such tension, in the material in balloon 84. Such tension detecting means, acting through the disc 112, functions automatically to vary the retarding force imposed on the material passing about groove 110 by imposing a retarding torque on means 103. Contact between run 134 and one or both of flanges 118 and 120 of the disc 120, when such disc is in either of the positions shown in Figs. 5 and 7 takes place at all times on the side of the disc which is travelling downwardly. The disc is travelling almost at right angles to such run of material at the line of contact. Furthermore, the speed of the disc 112 adjacent edges 162 and 164, where contact with the material is most forceful, exceeds the peripheral speed of groove 110. Thus material 134 does not tend to drive disc 112, when it contacts its flanges, but rather tends to retard it.

It will be appreciated from the above that the compensating device of the invention is simple and economical to make, and that it is substantially maintenance free. Because the disc 112 is positively rotated by the cord engaging the groove 110, the wear over the inner surfaces of the flanges of the disc is evenly distributed and thus the disc may be used for a long period without replacement. Contact between the inner material engaging surfaces of the disc 112 and the elongated flexible material occurs in directions so nearly tangential to the surfaces of the disc, and such light contact is required between the material and the surfaces of the disc to effect marked braking action at groove 110, that there is little if any tendency for such surfaces to scuff the material and to break the filaments thereof. It will also be appreciated that, once the tension which spring 136 exerts upon lever 70 has been adjusted, the device will operate with substantially complete freedom from attention to maintain the tension and thus the diameter of balloon 84 of the desired value.

Whereas for purposes of illustration I have shown and described a preferred embodiment of the twisting spindle balloon compensating device and the combination of such device with a multi-spindle twisting machine, it will be understood that within the scope of the invention the device is capable of considerable variation as to details and also as to the manner of its application. The invention is therefore to be defined by the scope of the claims appended hereto.

I claim as new the following:

1. A tension compensating device for elongated material travelling in the direction of its length from a first zone of initial tension into a second zone of greater tension, comprising means for detecting the tension in the material at the tension device, said tension detecting means including a roller guide deflected in response to changes in the tension in the material, means mounting the roller guide to allow such deflection, means constantly urging the guide roller in such direction as to oppose deflection by the material, a member positioned by the roller guide mounting means for variably retarding rotation of the roller guide by frictionally engaging a run of the material after it has left the tension detecting means, and means connecting the roller guide retarding member to the roller guide so that said roller guide retards the material with a variable force.

2. A tension compensating device for elongated material travelling in the direction of its length from a first zone of initial, substantially constant, tension into a second zone of greater, variable, tension, comprising means for detecting the tension in the material at the tension device, said tension detecting means including a roller guide deflected in response to changes in the tension in the material, means mounting the roller guide to allow such deflection, means constantly urging the guide roller in such direction as to oppose deflection by the material, a member positioned by the roller guide mounting means for variably retarding rotation of the roller guide by frictionally engaging a run of the material after it has left the tension measuring means, and means connecting the roller guide retarding member to the roller guide so that said roller guide retards the material with a variable force.

3. A tension compensating device for elongated material travelling in the direction of its length from a first zone of initial tension into a second zone of greater tension, comprising means for detecting the tension in the material at the tension device, said tension detecting means including a roller guide deflected in response to changes in the tension in the material, means mounting the roller guide for travel in such direction as to be variably deflected by the material, means constantly urging the guide roller in such direction as to oppose deflection by the material, a roller guide retarding member mounted to move with the roller guide, such retarding member engaging with variable force a run of the material after it has left the tension detecting means, and means connecting the roller guide retarding member to the roller guide so that said roller guide retards the material with a variable force.

4. A tension compensating device for elongated material travelling in the direction of its length from a first zone of initial tension into a second zone of greater tension, comprising means for detecting the tension in the material at the tension device, said tension detecting means including a roller guide deflected in response to changes in tension in the material, means mounting the roller guide for travel in such direction as to vary the amount of deflection of the material, means constantly urging the roller guide in such direction as to oppose deflection by the material, a roller guide retarding member connected to rotate with the roller guide and mounted to move with the roller guide in its deflection, such retarding member engaging with variable force a run of the material after it has left the tension detecting means.

5. A tension compensating device for elongated material travelling in the direction of its length from a first zone of initial tension into a second zone of greater tension, comprising a first fixed position guide engaging the material as it approaches the tension device, a second fixed position guide spaced therefrom, a roller guide engaging and driven by the material in its travel between the first and second fixed guides, a support for the roller guide comprising a lever mounted for oscillation about an axis transverse to the length of the lever, the roller guide being mounted on the lever, means constantly urging the lever against the force of the material deflected by the roller guide, a rotatable disc mounted on the lever, the disc

being so mounted that a run of material from the second fixed position guide extends roughly parallel to a side face of the disc, said side face of the disc variably engaging the material generally in accordance with the amount of displacement of the roller guide from its normal operating position, and means drivingly connecting the disc to the roller guide.

6. A tension compensating device for elongated material travelling in the direction of its length from a first zone of initial tension into a second zone of greater tension, comprising means for detecting the tension in the material the second zone thereof including a first fixed position guide engaging the material as it approaches the tension device, a second fixed position guide spaced therefrom, a roller guide engaging and driven by the material in its travel between the first and second fixed position guides, a support for the roller guide comprising a lever mounted for oscillation about an axis transverse to the length of the lever, the roller guide being mounted on the lever, means constantly urging the lever against the force of the material deflected by the guide roll, a roller guide retarding disc mounted on the lever, the disc being positioned adjacent to and drivingly connected to the roller guide, said disc having a slot transverse to its axis inwardly from its periphery and parallel to the broad surfaces thereof, the disc being so mounted that a run of material from the second fixed position guide extends through the slot in the disc and roughly parallel to the plane of the slot therein, said side walls of the slot engaging the material with a force which is variable generally in accordance with the amount of displacement of the roller guide from its initial operating position with the material just contacting a sidewall of the slot.

7. Apparatus for twisting elongated flexible filamentary material such as yarn in one continuous operation comprising a plurality of two-for-one twisting spindles each of the type which forms filamentary material extending therefrom into a free-flying first balloon, means associated with each spindle for imposing a predetermined back tension on such material, a two-for-one twisting device of the type forming and receiving filamentary material from a second free-flying balloon, said device including means for drawing in twisted material from the latter balloon, means for gathering together the twisted materials from the first balloons and leading such materials in gathered relation into the second balloon to form the latter, tension compensating means for maintaining said second balloon under yielding variable tension, said last named means acting to maintain the tension in the second balloon in balance with the sum of the tensions in the first balloons, and means for driving said twisting spindles and said twisting device in synchronism, said tension compensating means comprising means for detecting the tension in the material in the second balloon, said tension detecting means in-

cluding a roller guide deflected in response to changes in the tension, in the material, means mounting the roller guide to allow such deflection, means constantly urging the guide roller in such direction as to oppose deflection by the material, a member positioned by the roller guide mounting means for variably retarding rotation of the roller guide by frictionally engaging a run of the material after it has left the tension detecting means, and means connecting the roller guide retarding member to the roller guide so that said roller guide retards the material with a variable force.

8. Apparatus for twisting elongated flexible filamentary material such as yarn in one continuous operation comprising a plurality of two-for-one twisting spindles each of the type which forms filamentary material extending therefrom into a free-flying first balloon, means associated with each spindle for imposing a predetermined back tension on such material, a two-for-one twisting device of the type forming and receiving filamentary material from a second free-flying balloon, said device including means for drawing in twisted material from the latter balloon, means for gathering together the twisted materials from the first balloons and leading such materials in gathered relation into the second balloon to form the latter, tension compensating means for maintaining said second balloon under yielding variable tension, said last named means acting to maintain the tension in the second balloon in balance with the sum of the tensions in the first balloons, and means for driving said twisting spindles and said twisting device in synchronism, said tension compensating means comprising a first fixed position guide engaging the material as it approaches the tension device, a second fixed position guide spaced therefrom, a roller guide engaging and driven by the material in its travel between the first and second fixed guides, a support for the roller guide comprising a lever mounted for oscillation about an axis transverse to the length of the lever, the roller guide being mounted on the lever, means constantly urging the lever against the force of the material deflected by the roller guide, a rotatable disc mounted on the lever, the disc being positioned adjacent to and drivingly connected to the roller guide, said disc having a slot transverse to its axis inwardly from its periphery and parallel to the broad surfaces thereof, the disc being so mounted that a run of material from the second fixed position guide extends through the slot in the disc and roughly parallel to the plane of the slot therein, said side walls of the slot engaging the material with a force which is variable generally in accordance with the amount of displacement of the roller guide from an initial, operating position with the material just contacting a sidewall of the slot.
